UNITED STATES PATENT OFFICE.

CHARLES F. HUNTOON, OF PASADENA, CALIFORNIA.

BOLSTER SPRING SEAT STOP.

Application filed October 12, 1925. Serial No. 62,050.

The invention relates to improvements in truck bolsters of the type shown in Patent No. 1,210,478, January 2, 1917, and more particularly to the manner of holding the 5 spring seat block to prevent the same from shifting and breaking the cast end guides.

It is chiefly characterized by providing a stop or lug secured to the top wall of the inverted spring seat pocket, which lug is 10 engaged by a suitable recess in the upper surface of the spring block. The spring block, in other respects, fits loosely in the pocket.

It has been found that in many instances 15 in the present practice of loosely fitting a wooden or cast iron spring block into the wedge-shaped pockets in the ends of the bolster, the breakage of the end castings has been due to lateral shifting of the spring 20 block under the strain of the lurching and side swaying of the car body.

It would be manifestly impractical to secure the spring block in any ordinary manner to the end castings against lateral shifting, but it is entirely practical to attach a 25 stop against such shifting to the upper wall of the pocket because the upper wall is furnished by the truss members which are made of rolled steel material.

An object of this invention is to provide 30 such a stop which is simple and substantial and will not add materially to the cost of the bolster.

Further objects and advantages will 35 appear in the following description with reference to the accompanying drawings, in which an illustrative embodiment of this invention is shown.

In the drawings: 40 Figure 1 is an elevation of the truck bolster.

Fig. 2 is an inverted plan view.

Fig. 3 is a central section of Fig. 1.

Fig. 4 is a perspective view of the spring 45 block.

Fig. 5 shows the stop member.

In a trussed truck bolster the upper member is an inverted channel, bowed upward 50 in the center and having the ends bent upward to join the ends of the inversely bent flat lower member. The lower member is thickened at the ends to provide a shoulder for abutting with the outer ends of the web of the upper member to prevent shearing the 55 rivets, of which there are usually three at

each end, and which fasten the ends of the upper and lower members together. A cast iron end member is ordinarily used to enclose the ends of the truss for reinforcing it and providing lateral wearing and guide 60 surfaces for engaging with the truck side frames and for providing an inverted pocket, formed by the walls of the end member and the under surface of the lower truss member, into which is loosely fitted a cast 65 iron or wooden spring seat block.

In the present improvement a cylindrical stop member, having a concentric counter-bored hole, is placed under the middle rivet head with the head fitting in the counter-bored recess. This provides a shouldered projection secured to the upper surface of the pocket. 70

The spring block is provided with a recess in its upper surface which closely engages the stop member, while the remaining lateral surfaces of the spring block clear the adjacent surfaces of the pocket. 75

Referring in detail to the drawings, the truck bolster 1 receives, with limited pivoting, the center of the car bolster, which supports the end of the car, on the centrally located member 2. The ends 3 of the truck bolster 1 engage with openings in the truck side frame and rest on the car springs 4, and side rocking of the car is stopped by the side bearings 21. This is more fully illustrated in my Patent No. 1,176,063, granted March 21, 1916. 80

The upper truss member 5 is bowed upwardly in the center and the ends 6 are upturned to rest on the ends 7 of the flat lower truss member 8. The medial portions of 5 and 8 are spaced by the strut 9 and the ends 6 and 7 are secured together by the rivets 95 10, of which there are usually three, spaced as shown.

The inverted spring pocket 11 is formed at the ends of the bolster 1 by means of the end casting 12, which laterally encloses the 100 said ends and is secured to the marginal flanges 13 of the upper truss member 5 by the rivets 14. Side movement of the bolster 1 is stopped by the vertical shoulders 15 formed on the end member 12, which abut 105 the inner flanges of the openings in the truck frame.

Thus it will be seen that the pocket 11 is necessarily wedge-shaped in transverse section and the upper wall 16 formed by the 110

lower surface of the truss member 8 slopes inwardly. The spring seat block 17 fits loosely in the pocket 11 and is recessed as at 18 to clear other lateral surfaces.

5 To prevent lateral shifting, I provide a recess 19 in the upper surface of the spring block 17 which is adapted to closely engage with the stop 20 secured to the rolled steel member 8.

10 The stop 20 is cylindrical with a central hole 21 having the concentric recess 22 and is placed under the head of the middle truss rivet 10', with the rivet head 23 countersunk in the recess 22.

15 Thus the improvement is accomplished by the addition of one simple member 20, and a rivet 10', which is already in the bolster, is used for securing the stop in place.

It is manifest that with the car in motion, 20 sudden and severe shocks are received by the spring blocks, as for instance in a side lurch being stopped by the side bearing 21. Owing to the slope of the top 16 of the pocket 11, considerable force is developed to 25 drive the wedge-shaped spring block 17 outwardly against the end wall of the member 12, which may easily be sufficient to break the same.

It can also be seen that forces are 30 constantly being developed for shifting the spring block 17 about in the pocket 11, and that the shifting is now stopped in a very simple and efficient manner without weakening the spring block.

35 Although but one specific embodiment of this invention has been herein shown and described, it will be understood that the construction shown may be altered without de-

parting from the spirit of this invention as defined by the following claims.

I claim:

1. In a truck bolster having an inverted pocket formed at each end thereof, a cylindrical member secured to the upper wall of the pocket forming a shouldered projection, a spring seat block loosely fitting in said pocket and having a recess adapted to closely engage with said member. 40

2. In combination, in a trussed truck bolster having a channel-shaped upper truss member having upturned ends, a lower flat truss member joined at the ends to the web at the ends of the upper truss member by means of rivets, and end reinforcing member secured over the joined ends of the truss members, forming at each end an inverted pocket with an inwardly sloping top wall in which are located the heads of said rivets, a recessed disk member under the heads of one centrally located rivet, and a spring block fitting loosely in said pocket and having a recess adapted to engage said disk member. 45

3. In a truck bolster having inverted pockets having inwardly sloping top walls and a rivet head located therein, a recessed cylindrical member under the rivet head and receiving the head in the said recess and forming a shouldered projection, and a spring block loosely fitting in the said pocket and having a recess engaging said shouldered projection. 50

Signed at South Pasadena, California, 55 this 3rd day of September, 1925.

CHARLES F. HUNTOON.
